(57) **CLAIM**

The ornamental design for a monitor support arm, as shown and described.

DESCRIPTION

FIG. 1 is a perspective view of the monitor support arm according to the present design;

FIG. 2 is a front elevational view of the monitor support arm of FIG. 1;

FIG. 3 is a rear elevational view of the monitor support arm of FIGS. 1 and 2;

FIG. 4 is a right side elevational view of the monitor support arm of FIGS. 1-3, the left side elevational view being a mirror image of the right side elevational view;

FIG. 5 is a top plan view of the monitor support arm of FIGS. 1-3, the bottom plan view being a mirror image of the top plan view; and,

FIG. 6 is a perspective view of the monitor support arm of FIGS. 1-4 illustrating the pivoting of the monitor support arm about a pivot point thereof.

Throughout FIGS. 1-6 a mounting post to which the monitor support arm is attached and a mounting assembly for securing a monitor to the monitor support arm are shown in phantom lines for illustrative purposes only and do not constitute a part of the claimed design.
